EYEGLASS GUARD

Arthur R. Hilsinger, Maplewood, N. J.

Application February 10, 1933, Serial No. 656,077

1 Claim. (Cl. 88—50)

This invention relates to improvements in optical frames and more especially to the construction of guards for spectacles and eye glasses.

The principal objects of the invention are the provision of guards of the rocking-pad type wherein the pads are so designed as to be easily attached to the supporting area without distorting the same or marring the finish thereof or of the trued and finished frame and pads, which pads are readily replaceable, when desired, by a simple manipulation performed with a plier or other simple tool. Further objects of the invention resides in the fact that the degree of rock of the pad can be readily varied by means of a simple manipulation with a plier or other simple tool and also that both in the manufacture of the pad and in the operation of attaching the same to the supporting arm the quality of the precious metal on the surface of the interlocking parts of the pad and arm is not affected or altered as now commonly occurs, due to the shaving action which occurs in striking up the post of the present type of pad from a blank and due to the spinning of the end of such post during the riveting of the same to the supporting arm. Other advantages of my invention are hereinafter set forth.

At the present time the pad of the guards of eye glasses or spectacles are commonly secured to the lever arm elements so as to afford a self-locating or rocking engagement and usually this is accomplished by providing a post or stud member on a pad, which stud is inserted through an aperture in the lever arm and then a head is spun or otherwise formed on the free end of said stud so as to retain the stud in permanent engagement with such lever arm while permitting of the free rocking thereof, whereby the pad automatically accommodates itself to the nose of the wearer. In order to adjust a pad in or out, the lever arm is bent with pliers to space the pad the desired distance from the rim of the frame. However, frequently, in endeavoring to adjust the lever arm by such bending operation, the same is fractured and, in such event, because of the fact that the pad is riveted thereto, it is necessary that the optician or retail dealer handling the same return the entire frame to the manufacturer in order to have a new pad riveted to the lever arm. Furthermore, in the forming of the post or stud on said pad, which is usually accomplished by a stamping or striking-up operation performed on a suitable blank, the quality of the previous metal layer of the surface of the blank is deleteriously affected, as during the striking-up of the post, an elongation occurs which tends to rob the

surface portion of some of its coating. Again, when the up-setting or spinning operation is performed in securing the pad to the lever arm, there is still a further weakening of the quality of the coating, with the consequence that corrosion is far more likely to occur on the end of the stud and especially under the influence of perspiration or moisture than on any other part of the frame. 5

My investigations have led to the discovery that the foregoing objections can be avoided by employing my new guard construction and method of applying a pad to the supporting lever arm, all as hereinafter described in detail.

In the accompanying drawing in which I have illustrated certain preferred embodiments of my 15 invention

Figure 1 is an elevation of a pair of spectacles equipped with my improved guard;

Fig. 2 is a fragmentary detail elevation, partly in section, of the same;

Fig. 3 is a front elevation partly broken away 20 of the pad member, isolated;

Fig. 4 is a perspective view of the looped insert member of the pad, isolated;

Fig. 5 is a section on the line 5—5 of Fig. 1; 25

Fig. 6 is a front elevation, partly in section, of a pad and a pair of pliers showing the manner in which the spreading of the loop carried by the pad can be accomplished and Fig. 7 is a fragmentary edge elevation, partly in section;

Fig. 8 is an elevation of a metal pad equipped 30 with my improved loop attachment, isolated;

Fig. 9 is a front elevation of a modified form of pad; and

Fig. 10 is a vertical section on the line 10—10 35 of Fig. 9.

Referring to the drawing and the construction shown therein, the reference numeral 1 designates a bridge of an optical frame, such for example as the pair of spectacles illustrated, and 2 40 the lens rims in which are mounted lenses 3. The reference numeral 4 designates temple mountings and 5 the temples pivotally secured thereto. Guard-support or lever arms 6 are secured to the inner margin of the respective rims, 45 being usually soldered thereto, and said lever arms are offset to provide depending portions 7 having slotted apertures 8 formed therein adjacent the tip thereof.

Referring to the construction shown in Figs. 50 2 to 5 inclusive, composition pad members 9, formed of zylonite or other suitable shell or plastic compositions, are mounted on the depending portion of the lever arm in such a manner as to have relative rocking engagement 55

therewith, the same being accomplished by providing such pad member with a looped insert member 10, formed preferably from a wire or rod, which is anchored in the composition pad 5 during the molding thereof in such a manner that the flattened and expanded offset ends 11, 11' thereof are embedded between the opposing halves *a* and *b* of such composition pad. The eye or loop of such insert is of such an area 10 or expanse that prior to the spreading or expansion of said loop, the same can be readily inserted through the aperture 8 in the terminal of the guard support arm and when so inserted, can be spread or expanded into the position 15 indicated in the dotted lines in Fig. 2 so as to permit of rocking engagement of the pad with the depending portion 7 of such lever arm while preventing the accidental separation of these interlocking members from each other.

20 In Fig. 8, a form of metal pad is illustrated, the same being designated by the reference numeral 12. In this type of pad, a looped element or link 13 is secured to the rear face of the pad by means of solder, as designated by the 25 reference letter *c*, or in any other suitable manner. This pad, like the pad shown in Figs. 2 to 5 inclusive, can be secured to the depending portion 7 of the guard support arm by inserting the loop 13 through the slotted aperture 8 and 30 thereafter expanding the same in the manner previously described with reference to the loop 10 of the pad 9.

In the construction shown in Figs. 9 and 10, there is illustrated a still further form of composition pad, the same being designated by the 35 reference number 14 in which a looped insert member 10 is embedded between the two halves *d* and *e* of such pad, the latter being provided with an outwardly flaring recess *f* through which the loop or link of said insert projects and the 40 minimum diameter of such recess is slightly greater than the extreme normal width or expanse of the looped portion of such insert, whereby the section or portion *e* of said pad can be 45 applied over the looped end of the insert after the same has been flattened and after the ends 11, 11' thereof have been offset. To securely retain or anchor the insert member between the halves of said pad, and especially to prevent distortion of the insert at the shank thereof during 50 the spreading or compressing of the loop, I provide a washer 15, which is preferably about .005" in thickness and the central aperture *g* in said washer is of just sufficient diameter to permit of 55 the same being fitted over the shank portion of the insert member when the opposing wires are spot-welded together, as indicated in Fig. 4, and thereafter the ends 11, 11' may be flattened and upset. The insert member with the washer thus 60 applied thereto is molded between the two halves *d* and *e* of the composition pad.

In order to either apply or detach the pad to the depending portion 7 of the guard arm, I employ a pair of specially constructed pliers, the 65 same having handles 15 and 16 and opposing jaws 17 and 18. A conical pin or tooth 19 is secured to the jaw 17 and the jaw 18 has a bifurcated end into which the end of said pin is adapted to freely project when the jaws are 70 pressed. A stripper element 21 is secured to the inner face of the jaw 17, the said stripper being also bifurcated at its outer end, as indicated by the reference numeral 22, so as to permit of the free passage of the tooth or pin therethrough.

75 The operation of spreading the loop or eye 10,

or the corresponding loop 13 of the pad shown in Fig. 8, and interlocking the same with the portion 7 of the lever arm, is as follows:—The loop of the pad, before spreading such loop, is inserted through the slot 8 as indicated in Figs. 5 6 and 7. Thereupon pressure is then applied to the handles 15 and 16 with the result that the broad base of the pin or tooth 19 will effect the expansion or spreading of the eye 10 sufficiently to prevent the passage or escape of the 10 same through the aperture 8. When the loop has been expanded to the extent desired, the jaws of the plier are forced to open and by such movement the guard 21 will automatically strip 15 or free the eye 10 from the spreader or pin 19 and permit of the same being easily removed from the plier.

In order to detach a pad from its interlocked relation with the associated lever arm, the eye or loop is merely compressed to its original width 20 and thereupon the loop can be withdrawn through the aperture 8 and thus removed from the lever arm. The slight flexing of the metal during the attachment or removal of a pad from its frame is insufficient to seriously weaken the 25 same and consequently the same pad may be used for several different frames in the event of the breakage of a lever arm during adjustments thereof.

The adjustment of the degree of rock of my 30 improved guard, unlike the present type of rocking pads, is accomplished by simply exerting pressure with a pair of pliers upon the eye or loop to expand or spread the same to the extent 35 desired.

My improved loop construction, as distinguished from the post commonly employed heretofore, insures that the quality of the surface metal of such loop will not be in any way disturbed during manufacture or during the application of the pad 40 to the guard terminal regardless of the number of times that this may occur.

Among the various other advantages of my improved construction is the fact that the frame can first be completely finished and trued and 45 thereafter the pad is fastened thereto without affecting the adjustment, or in any way marring the finish, and thereby the manufacturing operations are substantially simplified, while at the same time the shape and finish of the pad are in 50 turn unaffected by the truing and finishing operations to which the frame has been previously subjected.

In the manufacture of my improved pad construction, there is a decided saving due to the 55 simplicity of the manufacture thereof as compared with the production of the usual pad embodying the aforesaid post construction, as not only are the original tool and die costs and the up-keep cost thereof for the production of my 60 pad very much less, but also the several successive drawing operations now required to draw or strike-up the present post from a blank and the excessive die wear attendant thereon are eliminated, since my loop element, especially that illustrated 65 in Fig. 4, can be formed complete, except for the spot welding operation which while preferred, is not essential, but a single stamping operation which effects the simultaneous cutting of the wire employed to the desired length, the formation of the loop, as well as the offsetting and flattening of the free ends of the insert. Furthermore, for the reasons heretofore explained, my improved pad construction peculiarly lends itself 70 to the employment of gold plated or other pre- 75

cious metal plated wire having a so-called base metal core.

As a practical example, the relative dimensions of the loop member and the receiving aperture, 5 the following dimensions, which in practice have proven to be highly satisfactory, are given:—

For an opening in the guard-support arm which is of oblong shape .040" x .60" loop is used which is formed preferably of a wire also of oblong section and of about .025" x .030" in section and the overall dimension of the loop when compressed is 10 about .57", thus leaving a clearance which admits of the free passage of the loop through the aperture in the guard arm of .003". Such a 15 loop, when compressed, or rather unexpanded, will have an eye of about .007" in diameter and this eye is expanded by the expanding tool about .010" to .025" with the result that the overall diameter of the expanded loop will approximate .070" to .085", the amount of expansion of the 20 coil depending upon the amount of relative rock which it is desired between the pad and the guard-support arm.

By the term "non-metallic plastic composition", 25 as used herein, I refer especially to pyroxylin plastics, as celluloid pyralin and zylonite, for example, and also synthetic resin condensation products, as bakelite or condensite, for example,

and other moldable plastics of a generally similar nature which adapts the same for use as the cover elements of optical nose guard pads.

Various changes in the above described construction can be made without departing from 5 the spirit of my invention as embraced within the scope of the appended claim.

Having thus described my invention, what I 10 claim and desire to obtain by United States Letters Patent is:—

A nose guard pad comprising two opposing rigidly inter-connected cover elements of non-metallic plastic material, one of said elements having a central aperture therein, a filamentary wire insert member of pliable metal having in- 15 integral offset ends which are embedded between said cover elements and having a looped terminal which projects through the central aperture of the apertured cover element and a washer enveloping the opposing wires forming the shank 20 of said loop and also embedded between the cover elements, said washer having a central aperture of sufficient size to just receive the wires of the shank and adapted to prevent undue separation of the wires in the shank of the loop where the 25 loop is expanded.

ARTHUR R. HILSINGER.
